(57) **CLAIM**

The ornamental design for a base station, as shown and described.

DESCRIPTION

FIG. 1 is a top left front perspective view of a base station in accordance with the claimed design;

FIG. 2 is a front elevation view of the design of FIG. 1; FIG. 3 is a rear elevation view of the design of FIG. 1; FIG. 4 is a top plan view of the design of FIG. 1; FIG. 5 is a left side elevation view of the design of FIG. 1; and,

FIG. 6 is a right side elevation view of the design of FIG. 1. The bottom plan view of the claimed design is omitted as it forms no part of the claimed design and/or is cumulative in view of the remaining figures.

The dash-dash broken lines in the figures (including, e.g., fasteners and openings for receiving such fasteners, etc.) represent unclaimed subject matter and form no part of the claimed design.

The dot-dash broken lines in the figures immediately adjacent solid lines represent a boundary between claimed and unclaimed subject matter and form no part of the claimed design.

The labels used herein to describe orientation (e.g., top, bottom, left, right) are merely for reference and are not intended to limit the interpretation of the design.
